IGNITER FOR GAS BURNERS

Eichey L. Swartz, Canton, Ohio, assignor of one-half to Kenneth B. Cope, Canton, Ohio

Application September 4, 1936, Serial No. 99,456

2 Claims. (Cl. 175—115)

The invention relates to igniters for gas burners and more particularly an electrical igniter for burners consuming manufactured or natural gas or any hydrocarbon vapor.

5 An object of the invention is to provide a novel form of electrical igniter which is automatically operated by the opening of the burner valve to produce a spark to ignite the gas escaping from the burner.

10 A further object is to provide a device of this character in which the spark is produced to ignite the gas escaping from a pilot burner which is automatically turned on before the main burner and automatically shut off as the main burner is 15 ignited therefrom.

A still further object is to provide a device of this character in which the circuit to the electrical igniter is automatically broken immediately upon the lighting of the pilot burner.

20 The above objects together with others which will be apparent from the drawing and following description, or which may be hereinafter referred to, may be attained by constructing the invention in the manner illustrated in the accompanying 25 drawing, in which

Figure 1 is a plan view of a burner provided with the improved igniter system; and

Fig. 2, a plan sectional view through the valve which controls the pilot burner and main burner.

30 Similar numerals refer to similar parts throughout the drawing.

A substantially horizontal gas burner of any usual and ordinary construction, such as ordinarily used upon gas ranges and the like arranged to 35 direct a substantially vertical flame, is indicated generally at 10, having the usual mixing chamber 11 located between the burner and the gas supply pipe 12 which communicates with the mixing chamber of the burner through the gas 40 valve indicated generally at 13 and pipe 14.

A pilot pipe 15 leads from the valve 13 to a pilot burner 16 located adjacent to the main burner 10 and the electrical igniter indicated generally at 17 is spaced from the main burner and 45 associated with said pilot burner and arranged to ignite the gas escaping therefrom so as to produce a pilot flame across the main burner 10 to light the same when the valve is moved to open position.

50 The valve includes a casing 18 communicating with the gas supply pipe 12 and provided with the threaded nipples 19 and 20 to which are connected the gas pipe 14 leading to the mixing chamber 11 of the main burner, and the pilot pipe 55 15 respectively.

The rotary valve 13 is mounted within the valve casing 18 and provided with the transversely disposed passage 21 communicating with the longitudinal passage 22 which communicates with the gas supply pipe 12. The usual handle 23 is 5 provided upon the rotary valve 13 for rotating the same in the direction of the arrow shown in the drawing so as to cause the transverse passage 21 therein to first register with the port 24 communicating with the pilot pipe 15 and later with 10 the port 25 communicating with the pipe 14 leading to the main burner.

These parts are so shaped and arranged that the passage 21 will be in partial communication with the port 25 before it has moved entirely out 15 of communication with the port 24.

A source of electrical energy is indicated at 26 and a wire 27 leads from one side thereof to the movable contact 28 which is carried upon and insulated from the rotary valve 13 as by the insulation 29.

20 A wire 30 connects the other side of said source of electrical energy to the spark coil 31, which is connected as by the wire 32 with a fixed contact point 33 which may be mounted upon and insulated from any suitable stationary portion of the structure, in the path of the movable contact 28, as by the insulation 34.

25 The spark coil 31 is also connected by a wire 36 with a lead 37 connected to one point 38 of 30 the spark plug 17, the other point 39 thereof being insulated therefrom in usual and well known manner as indicated at 40 and connected through the lead 41 and wire 42 to the other side of the spark coil 31.

35 In the operation of the device to light the burner 10, the valve handle 23 is turned in the direction of the arrows shown in the drawing, moving the transverse passage 21 of the valve into communication with the port 24 leading to 40 the pilot burner and thus admitting gas to the pilot burner.

45 At the same time the movable contact 28 will make contact with the fixed contact 33, closing the circuit through the spark coil to the spark plug and producing a spark across the gap between the points thereof so as to ignite the pilot burner 16. Continued movement of the valve handle 23 in this direction breaks the contact at 28—33 and brings the transverse passage 21 of 50 the valve into partial communication with the port 25 leading to the main burner before communication to the port 24 is entirely broken.

55 Thus the gas escaping from the main burner will be ignited by the flame from the pilot burner

16 and further movement of the valve handle in this direction shuts off the pilot burner so that the points of the spark plug are no further subjected to the flame while the flame from the main burner 10 may be turned up to any desired height.

5 From the above it will thus be seen that the pilot burner is automatically lighted as the valve is moved toward open position and automatically shut off as the main burner is lighted, and the 10 circuit to the spark plug is automatically broken immediately after the pilot burner is lighted so that there is no waste of gas or electrical energy and the points of the spark plug are not subjected to the continued heat of the flame.

15 I claim:

1. In combination with a substantially horizontal main gas burner for a stove arranged to direct a flame in a substantially vertical direction, a substantially horizontal pilot burner spaced from one side of the main burner and

disposed toward the main burner so as to direct a flame across the main burner, and an electric igniter for the pilot burner spaced from one side of the main burner so as not to be subjected to the heat of the flame of the main burner.

2. In combination with a substantially horizontal main gas burner for a stove arranged to direct a flame in a substantially vertical direction, a substantially horizontal pilot burner spaced from one side of the main burner and 10 disposed toward the main burner so as to direct a flame across the main burner and an electric igniter for the pilot burner spaced from one side of the main burner so as not to be subjected to the heat of the flame of the main burner, and means for momentarily operating the electric igniter and simultaneously admitting gas to the pilot burner.

RICHEY L. SWARTZ.
